(57) **CLAIM**

The ornamental design for a ring tower bag holder, as shown and described.

DESCRIPTION

FIG. 1 is a top front perspective view of a ring tower bag holder, showing our new design;

FIG. 2 is a front elevation view thereof;

FIG. 3 is a rear elevation view thereof;

FIG. 4 is a top plan view thereof;

FIG. 5 is a bottom plan view thereof; and,

FIG. 6 is a right elevation view thereof, the left elevation view being a mirror image thereof.

1 Claim, 4 Drawing Sheets
